UNITED STATES PATENT OFFICE.

NEILL A. CARTER, OF RAYNHAM, NORTH CAROLINA.

TOBACCO-CURING FURNACE.

SPECIFICATION forming part of Letters Patent No. 740,230, dated September 29, 1903.

Application filed September 15, 1902. Serial No. 123,524. (No model.)

To all whom it may concern.

Be it known that I, NEILL A. CARTER, a citizen of the United States, residing at Raynham, in the county of Robeson and State of North Carolina, have invented a new and useful Tobacco-Curing Furnace, of which the following is a specification.

This invention relates to tobacco-curing furnaces.

10 The object of the invention is in a ready, simple, thoroughly feasible, and practical manner to effect curing of tobacco and to eliminate from the procedure objectionable features heretofore present in furnaces of this 15 character.

A further object is to effect positive control of the heat, thereby to obviate overcuring.

With these and other objects in view, as will appear as the nature of the invention is 20 better understood, the same consists in the novel construction and combination of parts of a tobacco-curing furnace, as will be hereinafter fully described and claimed.

In the accompanying drawings, forming a 25 part of this specification, and in which like numerals of reference indicate corresponding parts, there is illustrated one form of embodiment of the invention capable of carrying the same into practical operation, it being understood that the elements therein exhibited may 30 be varied or changed as to shape, proportion, and exact manner of assemblage without departing from the spirit thereof, and in these drawings—

35 Figure 1 is a view in horizontal section through a tobacco-barn equipped with the furnace of the present invention. Fig. 2 is a view in plan, on an enlarged scale, of the mechanism for controlling the supply of fuel to the 40 furnace. Fig. 3 is a similar view of a draft or air-supply-regulating device. Fig. 4 is a view in front elevation of one of the furnaces.

Referring to the drawings, 1 designates 45 generally a barn, which may be of the usual or any preferred construction and provided with ordinary hanger-sticks, (not shown,) from which the tobacco to be cured is suspended. As the construction of the barn is a matter that will be largely controlled by the 50 tastes of the builder, any particular construction thereof is not shown. The barn in this

instance is shown as provided with two furnaces, and as each is a counterpart of the other a description of one will serve for both.

The furnace (designated generally 2) is 55 constructed of sheet metal and is provided with a flat bottom 3, a rounded top 4, and a funnel-shaped or constricted rear end 5. The front end 6 of the furnace has associated with it a draft-regulating device 7, (shown in detail in Fig. 3,) which will presently be described.

Arranged in the furnace is a series of burners 8, preferably of the kind adapted for burning liquid hydrocarbon—in this instance gasoline—the burners being arranged in pairs upon branch pipes 9, coupled to feed-pipes 10, arranged within and extending without the front wall of the furnace, the branch pipes being provided with valves 11, one for each burner, by which one or more burners of the series may be cut out of use, as desired. Access to the burners is had through sliding doors 12, arranged on one side of the furnace and working between guides or keepers 13, the doors being provided with suitable handles 14, by which they may be opened or closed, as desired. Each feed-pipe 10 connects exteriorly of the furnace with a branch pipe 15, carrying a fuel-regulating device 16, 75 presently described, and each branch pipe connects with one member of a three-way coupling 17, with which connects a pipe 18, leading to a tank 19, containing the gasoline or other hydrocarbon, the pipe 18 being provided with a valve 20, by which to cut off supply of fuel to the feed-pipes 10.

With the funnel-shaped or constricted rear end 5 of the furnace connects one end of a branch flue 21, the other end being connected 90 through suitable couplings with a main flue 22, extending without the front end of the barn and upward to the roof, the said flues being provided to carry off the fumes and smoke from the burning fuel.

95 The means for controlling the supply of air to the furnace comprises a disk 23, having a semicircular slot 24, adapted to coact with a similar slot 25, (shown in section in Fig. 1 and in dotted lines in Fig. 3,) the disk being held associated with the front of the furnace by a bolt or rivet 26, carrying a fixed pointer

27, the central portion of the disk being divided off into spaces indicating degrees of heat, ranging, say, from 100° Fahrenheit to 225° Fahrenheit, the temperature of the furnace being 100° when the disk is in the position shown in Fig. 3, at which time the smallest supply of air permissible will be supplied to the furnace. The disk is provided with a handle or knob 28, by which it may be turned.

10 The means for regulating the supply of fuel to the burners (shown in detail in Fig. 2) comprises a casing 29, through which fuel from the tank 19 passes, and in the casing is arranged an ordinary plug-valve, (not shown,) 15 to the shank 30 of which is connected a handle 31, constituting a pointer. The upper face of the casing is divided similar to the disk 23—viz., into divisions extending from 100 to 225, these divisions determining the quantity 20 of fuel to be supplied to the burners to give a certain degree of heat when the damper or disk 23 is set at the same point on the dial of the disk as that to which the handle 31 is set. Under the arrangement described when the 25 valve 30 and damper 23 are once adjusted the furnace will require no attention on the part of the operator to see that the desired temperature is maintained other than to keep a supply of fuel within the tank 19. Thus by 30 knowing what quantity of fuel the burners of either one or both of the furnaces will consume in a given time—say from sunrise to sunset—and the temperature desired to be determined it will only be necessary to set 35 the valves in the casings 29, when the operator may be assured that the results desired will be attained.

The furnaces have no communication with the external atmosphere except through the 40 openings in their fronts, so that danger of fire is reduced to a minimum.

It is of course a desideratum to prevent the smoke from the burning fuel from contacting with the tobacco to be cured, as such 45 would inevitably destroy its flavor, and by the provision of the flues 21 and 22 this is positively obviated.

The tank 19 will be supported at a level above that occupied by the burners and will 50 be by preference located at some distance

from the barn, so as to lessen danger of accident from fire.

All of the parts of the furnace of this invention are constructed with a view to simplicity, certainty of operation, and durability in use 55 and are such that in case of damage or breakage repairs may easily be effected.

As herein shown, the furnaces are supported above the floor of the barn upon legs 32; but it will be obvious that they may be otherwise 60 supported without departing from the spirit of the invention.

The outer ends of the furnace are herein shown as disposed flush with the ends of the barn, thus to bring the draft-regulating 65 means within easy reach of the operator; but it is to be understood that, if preferred, these ends may be disposed wholly within the barn, if found necessary or desirable.

What I claim is—

1. The combination with a tobacco-curing barn, of interiorly-arranged furnaces comprising casings and a plurality of hydrocarbon-burners within each casing, said casings being provided within the barn with openings and with sliding doors covering said openings through which access may be had to said burners and said casings being provided with means for admitting and for regulating the admission of fuel and air, accessible 75 exteriorly of the barn only.

2. The combination with a tobacco-curing barn having a wall provided with openings, of furnaces comprising casings connected with said openings and extending into the 85 barn, said casings being rearwardly contracted and connected by elbows with a single exit-flue for the unconsumed products of combustion, a hydrocarbon-burner within said casings, and means for admitting and 90 for regulating the admission of fuel and air, accessible externally of the barn only.

In testimony that I claim the foregoing as my own I have hereto affixed my signature in the presence of two witnesses.

NEILL A. CARTER.
